PLURAL COMPARTMENT CONTAINER FOR PAINTS OR THE LIKE

Ernest Bryant Crutchfield, Dayton, Ohio, assignor to The Mead Corporation, Dayton, Ohio

Filed Sept. 15, 1971, Ser. No. 180,934

Term of patent 14 years

Int. Cl. D9—01

U.S. Cl. D9—18

FIG-5

FIG-6

In the drawings:

FIG. 1 is a perspective view of a plural compartment container for paints or the like showing my new design.

FIG. 2 is a top plan view thereof;

FIG. 3 is a side elevational view thereof;

FIG. 4 is a bottom plan view thereof;

FIG. 5 is an end elevational view thereof; and

FIG. 6 is a sectional view on the line 6—6 of FIG. 2.

I claim:

The ornamental design for a plural compartment container for paints or the like, substantially as shown.
